UNITED STATES PATENT OFFICE.

JOEL GILMORE, OF HULL, TEXAS.

STUMP PULLER.

Application filed March 28, 1923. Serial No. 628,194.

To all whom it may concern:

Be it known that I, JOEL GILMORE, a citizen of the United States, residing at Hull, in the county of Liberty and State 5 of Texas, have invented certain new and useful Improvements in Stump Pullers, of which the following is a specification.

In carrying out the present invention, it is my purpose to provide a tree stump puller 10 that is a substantial improvement over similar devices, with which I am now familiar, the primary object thereof residing in the provision of such a device wherein the pulling element is operated by hydraulic means.

15 A further object of the invention is the provision of a tree stump puller, wherein the same is readily adapted to be transported from place to place, the device being further characterized by its simplicity of construction, durability and efficiency of operation, the same embodying relatively few parts, comparatively speaking, and these so correlated as to reduce the liability of derangement to a minimum.

20 25 The nature and advantages of the invention will be better understood when the following detailed description is read in connection with the accompanying drawings, the invention residing in the construction, combination, and arrangement of parts as 30 claimed.

In the drawings forming part of this application, like numerals of reference indicate 35 similar parts in the several views, and where-

Figure 1—is a top plan view of my machine.

Figure 2—is a side elevation thereof.

Figure 3—is a detail longitudinal cross 40 sectional view of a portion of the machine, hereinafter more fully described.

Figure 4—is an enlarged top plan of the fluid ejecting motor.

Figure 5—is a cross section through one 45 of the cylinders of this motor, and

Figure 6—is a fragmentary enlarged cross section through the end of the element shown in Figure 3.

Referring to the drawings in detail, 50 designates the frame of the machine, that is substantially rectangular in shape, embodying side bars 6, end bars 7, a transverse cross bar 8, adjacent the rear end bar and a longitudinal bar 9, between the end bars 55 and spaced a distance inwardly from one of the longitudinal frame bars 6. 10 des-

ignates the steering axle, 11 the front supporting wheels, 12 the rear axle, and 13 the rear supporting wheels.

Suitably supported between the bars 6 and 60 9 of the said frame 5 and adjacent the front end of the machine is a combustion engine, designated in its entirety by the numeral 14. This engine may be of any nature desirable, and I do not wish to be limited as to a 65 motor of any particular form, it only being understood that one end of the shaft 15 thereof extends inwardly of the frame, and is equipped with a sprocket gear.

Secured upon the said frame bars 6 and 70 9, as well as the end frame bar 7, and rearwardly of the combustion engine 14 is an oblong plate 16, upon the top face of which are four cylinders 17. It is preferable that these cylinders be cast with the plate 16, 75 for the purpose of reducing the cost of manufacture. As clearly shown in Figures 1 and 2, these cylinders are arranged in pairs, the front ends of each pair being spaced a suitable distance apart. Rectilinearly mov- 80 able within each cylinder is a piston 18, upon one end of a rod 19, the opposite ends of the rods being yoked at 20, and pivotally secured at 21 to certain ends of connecting rods 22'. 85

Also cast integrally with the plate 16, and at opposite ends of the cylinders 17 are pairs of bearing brackets 22, and journaled between each pair of brackets is a crank shaft 23 to the crank portions of which are connected the opposite ends of said connecting rods 22'. The outer end of each crank shaft 23 is provided with a sprocket gear 24, and trained over the gears of both shafts is a 90 sprocket chain 25. Upon the opposite end 95 of the shaft 23 adjacent the engine 14 is an additional sprocket gear, and between this gear and the gear upon the end of the motor shaft 15 is a sprocket chain 26.

Upon the front end of the plate 16 there 100 is positioned a fluid tank 27, which is provided with an inwardly and rearwardly directed fluid pipe 28. Each of the cylinders 17 are provided with inlet nipples 29, which have communication through the instru- 105 mentalities of a single plate connection 30, with the said pipe 28. The said cylinders 17 are further provided with outlet nipples 31, the cylinders of each pair having communication with the pipe 28, through pipes 32. The pipe 28 between the inlet and outlet 110 connections of the said cylinders 17 is

equipped with a control valve 33, this pipe being further provided at a point adjacent the tank 27 with a cut off valve 34.

Secured in any manner desirable between 5 the frame bars 7 and 8 of the machine frame is a relatively elongated open ended cylinder 35. The rear end of the cylinder projects beyond the frame bar 7, and is screw threaded at 36, the same having screw 10 threadedly disposed upon this end a hollow head 37, the front end of which is solid and pointed at 38. Slidable within the cylinder 35 is a relatively elongated plunger 39, the rear end of the same being equipped with 15 a desirable number of piston rings 40. The plunger 39 is preferably hollow as more clearly shown in Figure 6, and formed upon the projecting end of this plunger is a pin 41, which has secured thereon a cross arm 42. Upon the cylinder 35, and at opposite 20 sides thereof are laterally extending ears 43, and interconnected between these ears and adjacent the opposite ends of the said cross arm 42 are springs 44, the purpose of the 25 same being to normally maintain the plunger 39 rearwardly within the cylinder 35.

The said pipe 28 from the fluid tank 27 has connection at 45 with the said hollow head 37 upon the end of the cylinder, it being 30 of course understood that when my device is in use, the machine is adapted to be backed up for permitting the said pointed end of this head to engage the base of a tree A. When it is desired to employ my device 35 for pulling tree stumps, the machine as aforesaid is backed up to a tree A, that is in somewhat close proximity to the stump B to be pulled. After the machine has been moved to the position of Figures 1 and 2, 40 there is positioned around the tree A, a pair of cables 46 which carry pulleys 47. Secured to the extreme ends of the said cross arm 42 upon the end of the plunger 39 are the ends of a cable 48, these ends of the 45 cable having been previously passed over the said pulleys 47. Loose upon this cable is a pulley 49, which carries a hook 50, adapted for receiving one end of a cable 51, which has been engaged around and secured 50 to the said tree stump B. The valve 34 in the pipe line 38 is now open, while the valve 33 is closed. The engine 14 is started for effectively controlling the operation of the pistons within the cylinders, for withdrawing 55 the fluid from the tank 27, and consequently discharging the same to the pipes 32 again into the pipe 28, and consequently into the cylinder 35, for forcing the plunger 39 forwardly therein, for reducing the 60 length of the cable 48, which will effect a pull upon the cable 51 and consequently withdraw the stump from the ground. As the plunger 39 moves outwardly, the springs 44 are expanded, and after the tree stump 65 has been pulled, the motor is stopped, the

valve 33 opened, whereby through the force of the springs 44, the plunger moves backwardly within the cylinder, for returning the fluid to the tank 27.

In view of the above description, it is believed by me that it will at once be apparent to those skilled in the art, that I have provided a highly improved form of stump pulling machine, and one that is absolutely positive in its operation, and although I 70 have herein shown and described my machine as embodying certain detail structural elements, it is nevertheless to be understood that the same may be changed from time to time, without departing from the spirit and scope of the invention as claimed.

Having thus described my invention, what I claim as new, and desire to secure by Letters-Patent is:

1. In a machine of the class described, a frame, a cylinder disposed upon said frame, a plunger movable within the cylinder, a pointed head upon one end of said cylinder and adapted for engagement with the tree adjacent the stump to be pulled, a source of fluid supply, means for forcing said fluid into said cylinder for occasioning the outward movement of the plunger therein, a cable connected at its ends to the end of said plunger and engaging over pulleys upon said tree, and a connection between the cable and the stump to be pulled.

2. In a machine of the class described, a frame, a cylinder disposed upon said frame, a plunger movable within the cylinder, a pointed head upon one end of said cylinder and adapted for engagement with the tree adjacent the stump to be pulled, a source of fluid supply, means for forcing said fluid into said cylinder for occasioning the outward movement of the plunger therein, a cable connected at its ends to the end of said plunger and engaging over pulleys upon said tree, a connection between the cable and the stump to be pulled, said connection comprising a pulley loosely carried by said cable, and a cable surrounding the said stump and connected to said pulley.

3. In a machine of the class described, a frame, a cylinder mounted upon said frame and adapted for engagement at one end with a tree adjacent the stump to be pulled, a plunger movable within said cylinder, cable connections between one end of the plunger, the said tree and the stump to be pulled, and hydraulic means for forcing said plunger outwardly of said cylinder.

4. In a machine of the class described, a frame, a cylinder mounted upon said frame and adapted for engagement at one end with a tree adjacent the stump to be pulled, a plunger movable within said cylinder, cable connections between one end of the plunger, the said tree and the stump to be pulled, and

hydraulic means for forcing said plunger outwardly of said cylinder, and automatic means for returning the plunger within the cylinder.

5. In a machine of the class described, a frame, a cylinder mounted upon said frame and adapted for contact at one end with a tree adjacent the stump to be pulled, a plunger movable within said cylinder, a 10 source of fluid supply, means for forcing said fluid into said cylinder, for discharging the plunger therefrom, means for returning said plunger into the cylinder when said other means is cut off for returning the fluid to its source, and cable connections between the plunger, the said tree and the stump to be pulled.
15. In a machine of the class described, a frame, a cylinder mounted upon said frame

and adapted for contact at one end with a 20 tree adjacent the stump to be pulled, a plunger movable within said cylinder, a source of fluid supply, means for forcing said fluid into said cylinder, for discharging the plunger therefrom, means for returning 25 said plunger into the cylinder when said other means is cut off for returning the fluid to its source, cable connections between the plunger, the said tree and the stump to be pulled, said cable connections including a 30 cable secured at its opposite ends to one end of said plunger, pulleys upon the tree around which are engaged said cable, a cable arranged around the stump and a pulley connection between the two cables. 35

In testimony whereof I affix my signature.

JOEL GILMORE.
